UNITED STATES PATENT OFFICE.

GEORGE S. ALLEN AND ROBERT C. ELLRICH, OF SOUTHBURG, CONN.

SCREW-DRIVER.

SPECIFICATION forming part of Letters Patent No. 289,056, dated November 27, 1883.

Application filed September 19, 1882. (No model.)

To all whom it may concern:

Be it known that we, GEORGE S. ALLEN and ROBERT C. ELLRICH, citizens of the United States of America, residing at Southington, 5 in the county of Hartford and State of Connecticut, have invented certain new and useful Improvements in Screw-Drivers, of which the following is a specification, reference being had therein to the accompanying drawings, in which—

Figure 1 is a view of the screw-driver. Fig. 2 is a view of the parts of the same before the parts are put together. Fig. 3 is a longitudinal and central section of the handle and bolster, and Fig. 4 is a cross-section of the bolster. Figs. 5 and 6 are views of a die, and Fig. 7 is a sectional view of the bolster.

Our invention relates to screw-drivers, and its object is an improved article. The novelty 20 is in the bolster, for the most part, and consists in the means of fastening the handle in the same.

To enable others to make our improved screw-driver, we will give a detailed description 25 of the same and of its several parts.

That part of the shank A in the bolster, and for some distance from it, is a round steel rod, and the remaining part is made in the usual form. The tapering bolster B is cast 30 onto the shank, and has the tapering socket D, Fig. 7, in which are the feathers a, Fig. 4, and the swell or enlargement C on its upper end, as shown in Fig. 2. The part E of the handle F which enters the socket has the 35 notch b, and is tapering in opposite directions, as shown in Figs. 2 and 3. The other parts of the handle are in the usual form.

To put the bolster and handle together in our improved way, it is requisite that the 40 bolster be made of a ductile metal, or of a suit-

able alloy. A good alloy for the purpose, as it adheres with great tenacity to the shank, consists of tin, one hundred parts; antimony, fifteen parts; and copper, three parts. The handle may be driven into the socket, and the 45 swell on the bolster may be spun into the notch b on the part E of the handle. A better and more expeditious way is to place the bolster in a die having a tapering hole corresponding to the taper in the bolster, which is 50 shown in Fig. 5 and in section in Fig. 6, and to drive the bolster through the die, or until the wood of the handle appears below the die. In this simple way the ductile metal of the bolster is forced into the notch in the handle, 55 and the two parts are securely fastened together.

We are well aware that screw-drivers have been made with bolsters shrunk onto and cast onto the shanks, and that various means of 60 fastening the handles to the bolsters have been used; but

What we claim as our invention, and desire to secure by Letters Patent, is—

A screw-driver having the shank A, provided with a soft or ductile metal bolster, B, cast thereon, said bolster being formed with enlargement C at the open end, and a handle, F, having a depression, b, the whole being constructed to be set in place and then fastened by the inward swaging of the enlargement C, substantially as set forth.

In testimony whereof we affix our signatures in presence of two witnesses.

GEORGE S. ALLEN.
ROBERT C. ELLRICH.
